UNITED STATES PATENT OFFICE.

SIMON URIEL BRANSTETTER, OF VANDALIA, MISSOURI.

SUSPENDING DEVICE.

SPECIFICATION forming part of Letters Patent No. 391,450, dated October 23, 1888.

Application filed August 15, 1888. Serial No. 282,817. (No model.)

To all whom it may concern:

Be it known that I, SIMON URIEL BRANSTETTER, a citizen of the United States, residing at Vandalia, in the county of Audrain and 5 State of Missouri, have invented certain new and useful Improvements in Suspending Devices; and I do hereby declare that the following is a full, clear, and exact description of the same, reference being had to the annexed 10 drawings, making a part of this specification, and to the letters and figures of reference marked thereon.

Figure 1 of the drawings is a perspective view of my improved device, showing it connected to the waistband of a garment and one 15 of the tongues of a suspender attached to the device; and Fig. 2, a detail view in perspective of the device with one of the wires partly broken away.

20 The present invention has for its object to provide a device to be used for securing garments on the wearer, and to take the place of buttons commonly in use for securing thereto suspenders, which object I attain by the device constructed substantially as shown in 25 the drawings, and hereinafter described and claimed.

In the accompanying drawings, Fig. 1, A represents a portion of a waistband of a pair 30 of pants or other garment, having a hole, *a*, protected by an eyelet, *d*, for attaching thereto

the suspending device, as shown at B, and to the device is connected the tongue of a pair of suspenders.

The device is constructed of spring-wire, and 35 is formed of a single piece, the wire being bent double to form a loop, *c*, and its ends bent upon itself to form a shank, *e*, the extremities terminating in a hook, *b*, disposed at an angle of about thirty degrees. The loop *c* is bent inwardly on a curve, as shown, and extends down below and over the hook, and the extremities 40 of the wire forming the hook may be soldered together. The loop *c* increases in width toward its end, and its shape forms a very secure means of attaching thereto the tongue of a suspender. 45

Having now fully described my invention, what I claim as new, and desire to secure by Letters Patent, is—

50 The suspending device B, formed of spring-wire from a single piece and bent to form a hook, *b*, and inwardly-curved loop *c*, said loop extending down below and over the hook, substantially as and for the purpose set forth. 55

In testimony that I claim the above I have hereunto subscribed my name in the presence of two witnesses.

SIMON URIEL BRANSTETTER.
